THERMAL DRILL AND DRILLING PROCESS**Martin A. Ryan, Bartlesville, Okla., assignor to Phillips Petroleum Company, a corporation of Delaware****Application June 16, 1955, Serial No. 515,940****20 Claims. (Cl. 255—1.8)**

This invention relates to an improved process and drill for thermal drilling in an earth formation, particularly rock and rock-like formations. A specific aspect of the invention pertains to an improved nozzle for a thermal drill.

The use of thermal drills in piercing earth formations, particularly rock and rock-like minerals, is conventional. In one type of drill the flame is produced by burning a post-mixed combustible mixture of oxygen and fuel wherein all of the burning takes place outside of the blowpipe. Another type of thermal drill, such as that disclosed in the U.S. Patent 2,675,993 of George H. Smith et al., produces a flame in an internal combustion chamber into which the combustible mixture is injected before burning. Both of these types of thermal drills have limitations, particularly as to the rate of piercing or drilling a rock formation, because of the limited heat release possible with the type of mixing which they utilize. I have devised a thermal drill nozzle and burner which provides an improved method or type of mixing and simultaneously burning fuel and oxygen in a nozzle which effects vastly higher heat release than the burners of presently known thermal drills.

The principal object of the invention is to provide an improved thermal drill and process for drilling or piercing bore holes in an earth formation. Another object is to provide an improved thermal drill and drilling method which permit drilling at increased rates. Another object is to provide a thermal drill capable of increased heat release as compared with presently known thermal drills. A further object of the invention is to provide an improved drill and method of drilling which are particularly effective in drilling bore holes in iron-bearing rock, such as taconite. It is also an object of the invention to provide an improved drill nozzle for use in a thermal drill and in a drilling process. Other objects of the invention will become apparent from a consideration of the accompanying disclosure.

The invention comprises a process for thermal drilling wherein a fluid fuel is burned in admixture with oxygen with which it mixes by shearing turbulence occurring at the interface between an annular mass of one of the fluids moving through a combustion zone of circular transverse section in a burner nozzle and an axial mass of the other fluid swirling helically inside and adjacent the annular mass, directing the effluent flame and combustion gas against the formation or rock to be pierced or drilled so as to separate material therefrom by spalling and/or melting, and removing the separated material from the resulting bore hole; and a thermal drill which effects such a process. It has been found that this shearing turbulence method of burning effects a heat release of about 50 million. B.t.u. per cubic foot of mixing and burning space as compared with a heat release of about 3 million B.t.u. per cubic foot for a conventional burner. The drilling effectiveness of the improved burner and process is roughly proportional to the heat release. The improvement in heat release is believed to be due to more efficient mixing and burning of oxygen and fuel

2

resulting from or effected by the shear action and turbulence at the shear interface between the two masses of gas.

A more complete understanding of the invention may be had by reference to the accompanying schematic drawing of which Figure 1 is a longitudinal partial cross section of one embodiment of the thermal drill of the invention; Figure 2 is a plan view of the outlet end of the drill nozzle of Figure 1; Figure 3 is a longitudinal cross section of another embodiment of the improved drill nozzle of the invention showing a different means of effecting the helical swirl of the axially introduced fluid; Figure 4 is a cross section taken on the line 4—4 of Figure 3; and Figure 5 is a cross section taken on the line 5—5 of Figure 3. Similar elements in the various figures are correspondingly numbered.

Referring to Figures 1 and 2, thermal drill 10 comprises an upper distributing member 11 and a drill or burner nozzle 12 connected by a conduit 13 of variable length. Nozzle 12 comprises a burner housing 14 enclosing a burner tube 16 spaced apart therefrom to provide a cooling chamber 18. Burner tube 16 is threaded into housing 14 at 20. An axial gas distributor 22 is threaded into adapter 24 (by threads not shown) and cooperates with annular member 26 to form annular conduit or fluid inlet 28 at the inlet end of flame tube 16. An annular fluid distributor 30 is formed by members 22, 24, and 26. Fluid inlet conduit 32 is connected with annulus 30 by means of channel or conduit 34. Axial gas distributor 22 is provided with a core member 36 and with a series of swirl vanes 38 disposed in the annulus 40 surrounding core 36. Annulus 40 is connected directly with fluid inlet conduit 42.

Annular cooling chamber 18 is supplied with cooling fluid, such as water, from conduit 13 by conduit means including conduits 44, 45, and 46 and annular conduits 47 and 48. A plurality of conduits 44, 45, and 46 may be formed in the structure. Cooling fluid is ejected from the nozzle via ports 50 which are upwardly directed so as to eject the fluid upwardly in the annulus surrounding the drill nozzle and enclosed by the bore hole thereby adding to the lifting effect of the effluent gas. Radial drill teeth 52 having forward cutting edges 53 are rigidly attached to or formed integrally with nozzle housing 14 and preferably extend around the nose of the nozzle to flame outlet 56.

Swirl vanes 38 are several in number, such as shown in Figure 2, and are positioned in a helical pattern around core 36 in annulus 40 so as to impart a swirling helical movement of the mass of fluid introduced through conduit 42 to the inlet end of flame tube 16. These swirl vanes are symmetrically positioned at an angle in the range of 30° to 60° and preferably at about 45° in order to provide suitable swirl to the axial core of gas introduced to and maintained in the inlet end of the flame tube. Defined in terms of slope, the vanes should have a slope in the range of about 0.5 to 2. Fluid introduced through annulus 28 forms an annular mass of fluid adjacent the wall of the flame tube and adjacent the swirling core of gas produced by flowing gas between swirl vanes 38.

Fluid fuel distributing member 11 comprises an annular body member or sleeve 60 in which is journaled a core member 61 designed to rotate therein and provided with suitable packing material 62. Core 61 is retained in annular body member 60 by a flange 64 on the lower end of the core and by nut 65 threaded on its upper end and bearing on retainer plate 66. Axial conduit 68 in core 61 connects with inlet conduit 42 of burner nozzle 12 and connects on the upper end with nipple 70 which is attached to a swivel 71 which, in turn, connects with a supply conduit 72. Annular body member 60 is provided with an

nular fluid distributing conduits 74 and 75 which are connected to inlet nipples 76 and 77, respectively. Conduit 79 connects at its upper end with annular distributing conduit 75 and at its lower end with fluid inlet conduit 32 connecting with the burner nozzle. Conduit 80 in core 61 connects at its upper end with annular distributing conduit 74 and at its lower end with conduit 13 which supplies coolant to the drill nozzle.

In operation nozzle 12 is directed against the locus of the bore hole and the burner is ignited by any suitable means, such as a spark plug, not shown, or by means of a match or lighting torch before insertion in the bore hole. Oxygen or air is introduced, preferably through supply conduit 72, axially of the drill and burner, entering the flame or burner tube 16 axially thereof through conduit 42 and annulus 40 around swirl vanes 38 which impart a swirling movement to the incoming air thereby establishing an axially and helically moving mass of air or oxygen through the inlet end section of the flame tube. Simultaneously, fuel is introduced in an annular mass moving through the inlet end of the flame tube from annulus 28 by means of fuel inlet 77 and the connecting conduits including conduit 32. The rates of flow of fuel and oxygen are controlled so as to provide at least a stoichiometric excess of oxygen. The essential feature of the invention is the maintenance of a swirling, helically moving core of oxygen or fuel in the inlet end section of the burner tube and an annular mass of the other component of the combustible combination surrounding the helically moving core so that exceptionally efficient mixing and burning takes place at the shear interface of the two masses of fluid. While it is preferred to introduce the oxidant (free oxygen, air, or oxygen-enriched air) axially of the flame tube, it is also feasible to introduce the fuel to this section of the burner and the oxidant to the annulus surrounding the mass of core gas, with satisfactory results. The more suitable fuels are liquid hydrocarbons such as L.P.G., kerosene, gasoline, crude oil, fuel oil, etc. Butane, propane, and mixtures thereof are preferred to other fuels. The fuel may be introduced in vapor form to the drill head but it is preferred to vaporize the liquid fuel in the burner just before or as the same enters the flame tube by pressure drop and heat from the burner. In this manner the fuel enters the flame tube in vapor form and forms a vaporous annulus in the form of a sheath around the axial core of helically swirling oxidant.

Under some operating conditions when the melting exceeds the spalling ahead of drill nozzle 12 and the rate of slag formation is high, it may be desirable to rotate the drill nozzle so that radial teeth 52 extending longitudinally and across the end of the nozzle body so as to break up the slag and permit the removal of the resulting small particles in the gas stream emanating from the bore hole. When rotation is desired the same may be effected by conventional means such as that illustrated in the aforesaid Smith et al. patent, particularly Figure 5 thereof.

The preferred cooling fluid is water, but other fluids, such as steam, inert gas, air, or mixtures thereof, may be utilized with satisfactory results. Water is highly efficient in cooling and is particularly desirable in view of the conversion of the water to steam with concomitant vast expansion thereof and resulting assistance of the expanded coolant in blowing or ejecting separated particles of the earth formation or rock out of the bore hole. The coolant also assists in cooling the drill and drill stem.

Referring to Figures 3, 4, and 5, the nozzle of this embodiment of the invention is similar to that of Figures 1 and 2 in that it comprises basically a nozzle or burner housing 14 surrounding in spaced-apart relation a flame or burner tube 16 thereby providing a cooling chamber 18. This nozzle also has means for introducing and maintaining a helically swirling core of fluid in the feed end of the burner and means for introducing and maintaining an annular mass of gas surrounding the axial core. In the

embodiment shown in Figure 3, the gas introduced axially from conduit 42 is passed outwardly to annulus 82 via conduits 83. From annulus 82 fluid passes inwardly through tangential conduits 84 to cylindrical chamber 85 leading into the inlet end of flame tube 16 and contiguous therewith. As shown more clearly in Figures 4 and 5, the structure just described gives the fluid a first swirl in passing from axial inlet conduit 42 to annulus 82 through swirl tubes or conduits 83. As the fluid swirls in annulus 82 it passes through tangential tubes or conduits 84 leading into cylindrical chamber 85 which effectively swirls the gas being introduced axially of the flame tube in a helical pattern around the axis thereof as it progresses through the flame tube and effectively mixes and burns the surrounding sheath or annular mass of fuel at the interface between the two masses. Additional fluid (preferably oxygen) passes from annulus 82 through conduit 87 into annular chamber 88 from which it passes into the flame tube downstream of the inlet end via ports 89. In this manner the nozzle provides secondary oxidant for the fuel remaining unburned in the flame tube or combustion chamber as it reaches the vicinity of ports 89.

As in the nozzle of Figure 1, fuel is the preferred fluid introduced through conduit 32 to the inlet end of the nozzle. The fuel is passed from conduit 32 via conduit 90 to distributing annulus 30 from which it passes via annular inlet 28 into the inlet end of the flame tube and is directed downwardly in an annular mass adjacent the wall of the tube as in the nozzle of Figure 1.

In order to impart exceptionally high velocity to the effluent gas and flame, burner tube 16 is provided with venturi orifice or rocket motor exhaust nozzle 92, also known as a De Laval nozzle. The preferred included angle in this flared construction is 25 degrees since this imparts the greatest velocity to the effluent gas under average conditions; however, satisfactory performance is provided when the angle of this exhaust nozzle is in the range of 15 to 35 degrees.

Coolant is introduced into cooling chamber 18 from conduit 80 via connecting conduit 81. Chamber 18 surrounds venturi 92 which is subjected to maximum temperature conditions and is most in need of cooling. Additional cooling space around secondary air chamber 88 may be provided, if desired, but is not essential. The drill nozzle or burner and, particularly, the flame tube, is constructed of a high temperature alloy suitable for use in jet motor nozzles in order to withstand the high temperatures developed by the highly efficient method of mixing and burning provided by the nozzle of the invention.

Various modifications of the two nozzles illustrated in the drawing and described herein will occur to anyone skilled in the art. To illustrate, the jet nozzle type flame type of Figure 3 may be utilized in the drill nozzle of Figure 1 and, vice versa, the flame tube of Figure 1 may be utilized in the drill nozzle of Figure 3. It is also feasible to construct and operate the drill of Figure 3 without secondary oxidant ports 89. As pointed out above, it is feasible to introduce the fuel axially and the oxidant peripherally of the flame tube, although results are more satisfactory with axial introduction of the oxidant and peripheral introduction of the fuel. It is also feasible to operate the drill without radial drill teeth 52 and without rotation of the drill nozzle in view of the fact that the thermal drill of the invention will pierce or drill a bore hole in a rock formation by simply spalling and/or melting the rock in the path of the drill and blowing the separated material out of the bore hole without any cutting action of the teeth on the body of the nozzle when operating under most satisfactory conditions.

Certain modifications of the invention will become apparent to those skilled in the art and the illustrative details disclosed are not to be construed as imposing unnecessary limitations on the invention.

I claim:

1. A thermal drill comprising in combination a body member having fuel and oxygen inlets; a pair of conduits connecting with said inlets and extending from said member; a burner nozzle connected with the ends of said conduits remote from said member; a cylindrical internal combustion chamber of greater length than diameter and disposed axially in said nozzle having an outlet in the end thereof remote from said conduits; first conduit means in said nozzle connected with the inlet end of said combustion chamber and with one of said pair of conduits, said first conduit means being directed and disposed so as to introduce and pass fluid helically around the axis of said chamber; and second conduit means connected with the other of said pair of conduits and with the inlet end of said combustion chamber radially outside of said first conduit means, said second conduit means being directed and disposed so as to introduce and pass fluid along and adjacent the wall of said chamber parallel with its axis.

2. The drill of claim 1 including an inlet in said body member for a cooling fluid; an enclosed cooling chamber around said combustion chamber having at least one outlet adjacent the outlet end of said combustion chamber; third conduit means connected with last said inlet and with said cooling chamber remote from the outlet therein.

3. The drill of claim 2 including radical teeth on the outside of said nozzle extending longitudinally thereof.

4. The drill of claim 3 wherein said teeth extend over the outlet end of said nozzle to the outlet therein.

5. The drill of claim 1 wherein said body member comprises a sleeve surrounding a rotatable core journaled therein, said pair of conduits connecting said core with said nozzle and with said inlets during rotation of said core.

6. The drill of claim 5 including an attaching conduit surrounding said pair of conduits and rigidly attached to said core and to said nozzle at opposite ends; a conduit for coolant leading through said core to the interior of said attaching conduit; and a cooling chamber in said nozzle surrounding said combustion chamber having at least one outlet adjacent the outlet end of said nozzle, said cooling chamber being connected by conduit means leading from the interior of said attaching conduit so as to provide a flow path for coolant through said drill and out said at least one outlet.

7. The drill of claim 1 wherein said first conduit means comprises a first annulus coaxial with and opening into said chamber, and spaced-apart baffles in said first annulus arranged to direct fluid around the core of said first annulus as it passes therethrough to said chamber, said first annulus being connected with said one of said pair of conduits; and wherein said second conduit means comprises a second annulus opening into said chamber radially outside of said first annulus and concentric therewith, said second annulus being connected with the other of said pair of conduits.

8. The drill of claim 7 including a cooling chamber in said nozzle surrounding said combustion chamber having outlet ports adjacent the outlet end of said combustion chamber extending out through the wall of said nozzle; a rotatable core in said body member journaled therein and rigidly attached to the inlet end of said nozzle by an axial conduit surrounding said pair of conduits; a third conduit through said core leading into said axial conduit for introducing coolant to said nozzle; and conduit means connecting said axial conduit with said cooling chamber.

9. The drill of claim 1 wherein said first conduit means comprises a cylindrical chamber which is connected at its open end to the inlet end of said combustion chamber and is adjacent and coaxial with said combustion chamber of smaller diameter than same, a plurality of conduits tangentially entering said cylindrical chamber, an annular

conduit connecting the outer ends of the tangential conduits, said annular conduit being connected with said one of said pair of conduits; and wherein said second conduit means comprises an annulus adjacent the periphery of said combustion chamber, opening into the end of said combustion chamber in a direction longitudinal to same, said annulus being connected with the other of said pair of conduits.

10. The drill of claim 9 including a cooling chamber in said nozzle surrounding said combustion chamber having outlet ports adjacent the outlet end of said combustion chamber extending out through the wall of said nozzle; a rotatable core in said body member journaled therein and rigidly attached to the inlet end of said nozzle by an axial conduit surrounding said pair of conduits; a third conduit through said core leading into said axial conduit for introducing coolant to said nozzle; and conduit means connecting said axial conduit with said cooling chamber.

11. The drill of claim 1 wherein the outlet from said combustion chamber is a venturi rocket motor exhaust nozzle having an angle of divergence in the range of 15 to 35°.

12. The drill of claim 11 wherein said angle is 25°.

13. A thermal drill nozzle comprising a housing; a burner tube of greater length than diameter and of circular transverse section within said housing; means for introducing fluid to the inlet end of said tube longitudinally along the periphery thereof to form a fluid annulus; means for introducing fluid to said inlet end axially of said tube and in a helical pattern around the axis thereof of adjacent said fluid annulus; radial drill teeth on the periphery of said housing adapted to cut surrounding material when said nozzle is rotated.

14. The nozzle of claim 13 including an annular cooling chamber intermediate said housing and said tube; ports leading from said chamber through said housing adjacent the outlet end of said nozzle; and a fluid inlet to said chamber adjacent its end opposite said ports.

15. A process for thermal drilling in an earth formation which comprises burning a mixture of a combustible fluid fuel and free oxygen-containing gas in an elongated confined combustion zone of circular transverse section and having a greater length than diameter at the shear interface between an annular mass of one of the components of said mixture passed longitudinally along the periphery of said zone and an axial mass of the other component swirling helically adjacent said one component; directing effluent combustion gas and flame from the outlet of said zone against an earth formation so as to separate material from said formation in the path of the effluent and form a hole therein; and removing separated material from the hole.

16. The process of claim 15 wherein said fuel is passed along the periphery of the combustion zone.

17. The process of claim 15 wherein oxygen is passed along the periphery of the combustion zone.

18. The process of claim 15 wherein said earth formation comprises rock.

19. The process of claim 15 wherein said fuel comprises a normally liquid hydrocarbon.

20. The drill of claim 9 including an annulus around said combustion chamber between the ends thereof, ports connecting said annulus and said combustion chamber near the outlet of the latter, and conduit means connecting said annulus and said annular conduit.
